US0D1035661S

(12) **United States Design Patent** (10) **Patent No.:** **US D1,035,661 S**
(45) **Date of Patent:** ** *Jul. 16, 2024

(54) **MONITOR FOR COMPUTER**

(71) Applicant: **LG ELECTRONICS INC.**, Seoul (KR)

(72) Inventors: **Hyeongyeol Kim**, Seoul (KR); **Daihyung Ryu**, Seoul (KR)

(73) Assignee: **LG ELECTRONICS INC.**, Seoul (KR)

(*) Notice: This patent is subject to a terminal disclaimer.

(**) Term: **15 Years**

(21) Appl. No.: **29/821,550**

(22) Filed: **Dec. 30, 2021**

(30) **Foreign Application Priority Data**

Dec. 23, 2021 (KR) 30-2021-0062073

(57) **CLAIM**

The ornamental design for a monitor for computer, as shown and described.

DESCRIPTION

FIG. 1 is a front perspective view of a monitor for computer showing our new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the monitor for computer that form no part of the claimed design.

1 Claim, 7 Drawing Sheets
